UNITED STATES PATENT OFFICE.

WILLIAM S. ELLIOTT, OF PITTSBURG, PENNSYLVANIA.

WATER-TUBE BOILER.

No. 850,358.

Specification of Letters Patent.

Patented April 16, 1907.

Application filed June 15, 1906. Serial No. 321,836.

To all whom it may concern:

Be it known that I, WILLIAM S. ELLIOTT, a citizen of the United States, residing at 6509 Susquehanna street, Pittsburgh, in the county of Allegheny and State of Pennsylvania, have invented or discovered new and useful Improvements in Water-Tube Boilers, of which the following is a specification.

My invention relates to water-tube boilers; and its object is to provide a boiler of this type which shall have a definite circulation in its feed section, chamber, or compartment and which has such connections with the remainder of the boiler as will permit no cycle of circulation therewith, but will supply thereto water as it is evaporated therefrom.

Another object is to provide a maximum heating-surface within a given setting and at the same time to utilize a portion of this additional surface as a support for the roof of the fire-chamber.

These and other objects will appear in the description following.

Referring to the drawings which constitute a part of this specification, Figure 1 is a vertical section taken on 1 1 of Fig. 2, and Fig. 2 is partly a front elevation and partly a cross-section on the line 11 11 of Fig. 1.

On the drawings, 1 represents an upper steam and water drum or receptacle extending in the type of boiler shown preferably from the front to the rear wall; but it is to be understood that my invention is not restricted to boilers like the one shown when the principles which distinguishes my invention are employed.

2 is a lower water drum or receptacle, which is shown as extending from the rear wall preferably to the rear side of the bridge-wall 3, which extends transversely of the setting and is placed sufficiently to the rear to provide the required space for the fire-box 4, one of the grate-bars thereof being shown at 5.

The drums 1 and 2 are shown parallel and connected together by several longitudinal rows of tubes 6. I have shown eight of these rows; but the number of rows may be varied, and the manner of connecting them with the drums may be by means of curved tubes, as shown, or by any other suitable expedient.

I have shown two baffle-walls 7 and 8, the former passing between the fourth and fifth transverse rows of tubes 6 and extending from the drum 2 upwardly, so as to leave the space 9 between its upper edge and the drum 1 for the passage of the heat and furnace-

gases. The baffle-wall 8 is shown between the eleventh and twelfth transverse rows of tubes 6 and extends downwardly from the drum 1, so as to leave the space 10 between its lower edge and the drum 2 for the passage of the heat and furnace-gases. I have thus divided the space occupied by the tubes 6 into three serial passes—namely, the up-pass 11, the down-pass 12, and the up-pass 13—from which the gases pass around the drum 1 into the stack connection 14.

In the drum 1 I have placed the transverse partition 15, which I have shown in a plane between the tenth and eleventh of the transverse rows of tubes 6, this partition being provided above the water-line with holes 16 in order to connect the steam-spaces of the two compartments or receptacles of the drum, the front compartment or receptacle being 17 and the rear 19.

I divide the drum 2 into the compartments 20 and 21 by means of the transverse partition 22, which is placed so as to leave in the rear thereof one or more transverse rows 80 of tubes 6 in front of the partition 15. I have shown the partition 22 between the ninth and tenth rows of tubes.

While I have described the location of the baffle-walls and the partitions with great minuteness, I do not limit myself to the placing of the baffle-walls so as to leave any definite number of tubes in the front or the rear thereof. The front baffle-wall should divide the tubes connected to the compartment 18 90 into two sections, and the rear baffle-wall shall likewise divide the tubes connected to the compartment 19 into two sections. The partition 22 should be placed as above described.

The word "compartment" is not to be limited to a division of a drum, but includes as well distinct separate drums however arranged, provided they are so related and connected by tubes to secure the circulation and other functions by means substantially equivalent.

23 is the inlet for the water to the boiler, and it preferably leads into the compartment 19.

24 is the blow-off pipe for mud-drum compartment 21.

Extending downwardly from the front end of the drum 1 are the tubes 25, which are connected, by means of the individual junction-boxes 26, to the front ends of the tubes 27, which are inclined rearwardly and up-

wardly above the fire-box 4 and finally are bent upwardly and enter the drum 1 in front of the tubes 6. The roof 28 of the fire-box is supported on the inclined portion of the tubes 27, the space above the roof 28 receiving heat through the roof and between the tubes 27 beyond the rear end of the roof. The front end of the boiler is thus placed where there will be but slight agitation due to the escape of steam-bubbles through the water, and it is from this portion of the drum that I prefer to take the steam for use, the pipe 29 being the steam-outlet, which may be joined by a similar pipe from a second boiler or pair of drums or their equivalents in the same or different settings.

The junction-boxes 26 are provided with the end caps 30, which are within the open pockets 31, into which a tool may be admitted for the removal of said caps.

If preferred, the blow-off pipe 32, which is connected to the bottom of each junction-box, may be provided.

The heat and gases issuing from the fire-box will pass up among the tubes 6 in the pass 11, through the passage 9, down among the tubes in the pass 12, through the passage 10, up among the tubes in the pass 13, and out through the connection 14 into the stack. This course of the gases will cause the tubes in pass 11 to be heated more highly than those in the pass 12 and those in the latter pass to be heated more highly than those in the pass 13. This inequality of heating will cause an upflow of water in the tubes 6 of the pass 11, a downflow of water in those tubes in the pass 12 that are connected to the drum or compartment 20, an upflow in those tubes in the pass 12 that are connected to the drum or compartment 19, and a downflow in the tubes in the pass 13. Thus there will be a cycle of circulation of water from the drum or compartment 19 down the tubes in the rear of the baffle-wall 8 to the drum or compartment 21 and up some of the tubes in front of the baffle-wall 8 to the drum or compartment 19. The circulation in this cycle will be sufficiently slow to permit the foreign matter in the water to settle in the mud-drum 21 and yet sufficiently fast to keep the tubes well wetted to prevent their burning. All scale formed in this cycle will also settle in the drum 21.

A cycle of water circulation will exist in front of the partition 15 or its equivalent, the water passing up from the drum or compartment 20 in front of the baffle-wall 7 to the drum or compartment 18 and down the tubes at the rear of the said baffle-wall and in front of the partition 22 or its equivalent to the drum or compartment 20.

The tubes between the partitions 15 and 22 supply water from the rear cycle to the front cycle as fast as it is removed from the latter. The upflow in these tubes will there-

fore be slow, and the water transmitted by them will be comparatively free from sediment and scale.

A third cycle of water circulation will evidently exist from the drum or compartment 18, down the tubes 25, through the junction-boxes 26, and up the tubes 27 to the said drum or compartment 18. This cycle is added to the other parts of the boiler without any additional depth of the boiler-setting, as it is entirely over the grate. Not only is this additional heating-surface provided, but a support is already provided for the roof of the fire-box, which saves the construction of arches and otherwise simplifies the construction. Even without the said third cycle the remaining features of my invention would in no wise be sacrificed, as they would act substantially the same whether this cycle were present or absent.

I claim—

1. In a boiler, an upper drum, a partition therein dividing the same into front and rear compartments, a lower drum, a partition dividing the same into front and rear compartments, tubes connecting the front compartments, tubes connecting the rear compartments, tubes connecting the lower rear compartment and the upper front compartment, and a baffle between the tubes common to the rear compartments.

2. In a boiler, an upper drum, a partition therein dividing the same into front and rear compartments, a lower drum, a partition dividing the same into front and rear compartments, tubes connecting the front compartments, tubes connecting the rear compartments, tubes connecting the lower rear compartment and the upper front compartment, and means for causing a cycle of circulation between the said rear receptacles.

3. In a water-tube boiler, upper front and rear receptacles, lower front and rear receptacles, tubes connecting the front upper and lower receptacles, tubes connecting the rear upper and lower receptacles, tubes connecting the rear lower receptacles with the upper front receptacle, baffling dividing the first-named tubes, and baffling dividing the second-named tubes so as to cause two cycles of circulation.

4. In a water-tube boiler, an upper front and rear receptacle, a lower front and rear receptacle, tubes connecting the front upper receptacle with the front lower receptacle, tubes connecting the rear upper receptacle with the lower rear receptacle, and means for causing an up and down circulation in the tubes connecting the rear receptacles and an up and down circulation in the tubes connecting the front receptacles.

5. In a water-tube boiler, an upper front and rear receptacle, a lower front and rear receptacle, tubes connecting the front upper receptacle with the front lower receptacle,

tubes connecting the rear upper receptacle with the lower rear receptacle, means for causing an up and down circulation in the tubes connecting the rear receptacles and an up and down circulation in the tubes connecting the front receptacles, and means for supplying water from the lower rear receptacle to the front upper receptacle.

6. In a water-tube boiler, a lower mud-drum, an upper steam and water drum parallel therewith, a furnace in front of the mud-drum, junction-boxes located between the levels of the mud-drum and the steam and water drum, and tubes connected at their lower ends to said junction-boxes and at their upper ends to the upper steam and water drum, one of the tubes connected to each junction-box forming a part of the roof of the furnace.
- 15 7. In a water-tube boiler, a lower mud-drum, an upper steam and water drum parallel therewith, a furnace in front of the mud-drum, junction-boxes located between the levels of the mud-drum and the steam and water drum, and tubes connected at their lower ends to said junction-boxes and at their upper ends to the upper steam and water drum, one of the tubes connected to each junction-

box forming a part of the roof of the furnace and supporting the furnace-covering.

8. In a water-tube boiler, steam and water drums, mud-drums parallel thereto, water-tubes connecting steam and water drums and the mud-drums, a furnace in front of the mud-drum, junction means near the front wall, tubes connecting it to different portions of the steam and water drums and extending over the furnace, and baffle-plates above the said junction means and over the furnace.

9. In a water-tube boiler, steam and water drums, mud-drums parallel thereto, water-tubes connecting steam and water drums and the mud-drums, a furnace in front of the mud-drum, a series of water-chambers near the front wall, tubes connecting these chambers to different portions of the steam and water drums and extending over the furnace, and baffle-plates above the tubes and over the furnace.

Signed at Pittsburg, Pennsylvania, this 50
7th day of June, 1906.

WILLIAM S. ELLIOTT.
